Wm H McLellan

UNITED STATES PATENT OFFICE.

WILLIAM H. MCLELLAN, OF NEW ORLEANS, LOUISIANA, ASSIGNOR TO ST. CHARLES STREET RAILROAD COMPANY, OF SAME PLACE.

IMPROVED FARE-BOX.

Specification forming part of Letters Patent No. 63,804, dated April 16, 1867.

To all whom it may concern:

Be it known that I, W. H. MCLELLAN, of the city of New Orleans, parish of Orleans and State of Louisiana, have invented a new and useful Improvement in Horse-Car and Omnibus Fare-Boxes; and I do hereby declare the following to be a full, clear, and exact description of the same, reference being had to the annexed drawing, forming part of this specification, in which—

Figure 1 is a sectional view in perspective, and Fig. 2 a similar view of my invention in its completed state, as when in actual use, as seen from the inside of a car.

My invention supersedes the necessity of employing collectors on horse-cars and omnibuses; and it consists of a combination of a series of tilts, a sliding shelf and springs, so arranged as to enable passengers themselves to deposit the fare and secure its admission into a locked cash-box, with a lattice-screen of wire on the front and rear sides of the apparatus, which enables passengers and driver to see that the fare has been paid, and at the same time prevents the abstraction of the money, and a lever-check by which the driver is enabled to prevent the payment of fares while he is absent from his post.

In the construction of my invention, wood, brass, iron, or any other suitable or two or more different materials may be employed, as the taste and fancy of the maker may dictate, and it may be of any convenient external configuration or form. My usual plan is to construct the outside box of wood, and I prefer the form represented in the drawings as being at once symmetrical and convenient in its proportions.

Inside the outer box and in its front and rear sides are arranged the tilts, sliding shelf, springs, and other parts that constitute my invention, and which, by reference to the drawings, I shall now proceed to describe in detail.

A is a bent lever or push-arm; B, a vibrating or partially revolving door and shelf, or, as I technically call it, a "tilt." C is also a tilt, and D a sliding shelf. These parts are all connected with each other by a system of links or connecting-rods, and their action is conjoint and simultaneous.

The operation of my invention is as follows: The knob F being pushed inwardly, the push-arm A acts, by means of the connecting-link a, upon the tilt B, and causes it to revolve sufficiently upon its axis to establish an opening at its upper end for the reception of the fare into the box, while at the same time the box is closed, at a point a little below the opening, by the partial revolution in an upward direction, of the other or lower end of B, and it remains closed until the knob is relieved from pressure. Pressure being removed from the knob K, tilt B is instantly brought back to its closed or normal position, and firmly held in such position until the knob K is again subjected to pressure by the superior gravity of the ends o and s of the tilts C and B, which said ends are made very much heavier than the opposite ends u and v of said tilts; in order to produce this result. The same result may be attained by the insertion of a helical or other suitable spring at b, so placed as to press constantly against the upper end of the bent lever A in such manner as to keep knob K in proper position to be pushed in by the next passenger who wishes to deposit a fare. No spring is shown upon the drawings, but the same does not form an element of my claim, and any mechanic of ordinary skill will readily perceive how it may be introduced.

When tilt B assumes its normal position its lower end becomes an inclined plane, down which the fare slides and falls upon tilt C, where it is exposed to the view of the passengers and driver through the metallic lattice-openings E and G, until the next fare is deposited. Tilt C is connected to tilt B by means of link e, and to sliding shelf D by link d. The connection is in such wise that when B is open C is open and D closed, so that when the fare drops off C, it falls upon D, where it remains until C is again closed. As C closes D opens, and the fare is precipitated into the locked receptacle or cash-box H, where it remains until withdrawn by the cashier or other person appointed for such purpose.

In order that the driver and the passengers may know that the fare has been deposited, openings are made on the front and rear sides of the box, between tilts B and C. These

openings are covered by a lattice-screen of strong steel, iron, or brass wire, so constructed that the interstices are sufficiently large to allow the fare as it lies upon tilt C to be clearly discerned both from the front and rear. It will be observed that this lattice of wire affords a far more secure bar against predators than glass, while at the same time it is free from the obscuration to which glass is subjected from smoking lamps. It cannot, in fact, be obscured by smoke, but presents at all times a reliable protective medium through which the fare can be distinctly seen. If occasion call the driver temporarily off the car, a turn of the lever J fixes the knob F immovably in position, thus effectually preventing the deposition of a fare during his absence, and preventing the disputes that so frequently arise as to whether the fare has been really paid or put into the box. The locking of the knob K by a turn of the lever J is effected through the agency of the projecting pin q, which, when lever J is turned interposes behind the part t, which, it will be seen, is connected by the bar or rod w to said knob K. A partial revolution of the lever J partially revolves projecting pin q, because they both project from the same shaft and have a common center, and so the latter is brought into position behind part t, and thus holds knob K immovably in place.

The advantages of my invention are manifold, and I proceed now briefly to point out some of them. It enables the passengers to deposit the fare in the cash-box, and hence allows the driver to give a more constant attention to his animal and the car, a mere glance back being all that is required, after each passenger has entered the car, to tell him whether the fare has been deposited or not. In all car fare-boxes with which I am acquainted, but particularly in the case of J. B. Slawson's patented box, the part corresponding with tilt C is the last obstruction or stopping-place of the fare before it enters the locked cash-box, and as each fare is put into the

box the driver is required to pull a wire in order to get the fare into the money-box by a partial revolution of said part. In doing this an opening is made through which a hand may be inserted into the cash-box and its contents taken out if the glass in front of it should be broken. In my invention not only is the above-mentioned extra service of the driver dispensed with, but an effectual check against dishonesty is provided by the sliding shelf D, which, as we have seen, is always closed by the opening of tilt C and interposed to protect the deposit within the cash-box. If, therefore, the lattice of wire were broken by an instrument, or quite removed so that a thief could insert his hand within the box, he could only, in consequence of the interposition of D, get at the single fare that might be lying on tilt C. Another advantage of my invention over Slawson's box results from the obvious superiority of my tilts over the fixed incline planes used in the latter, and in the non-use of the knife employed in the same. Still another advantage of my invention is found in the substitution therein of the metallic screens in lieu of glass, and such other substances as are commonly used, by which I secure a view of each fare as it is put into the box, despite smoking lamps, and at the same time provide a more durable and efficient barrier against predators; and, finally, by the introduction of the lever J, I avoid all possible chance of contention as to the payment of fares between the driver and passengers.

Having thus described my invention, what I claim, and desire to secure by Letters Patent, is—

The combination of the push-arm A, tilt-door and shelf B, tilt C and sliding shelf D, when these several parts are constructed and arranged for conjoint operation, as described, for the purpose set forth.

WM. H. MCLELLAN.
